CLAIM

An ornamental design for an information storage disk cartridge, as shown and described.

DESCRIPTION

FIG. 1 is a top perspective view of an information storage disk cartridge on an enlarged scale;

FIG. 2 is a front elevation of FIG. 1;

FIG. 3 is a top plan view of FIG. 1;

FIG. 4 is a rear elevation view of FIG. 1;

FIG. 5 is a side elevation of FIG. 1;

FIG. 6 is a bottom plan view of FIG. 1; and,

FIG. 7 is an other side elevation of FIG. 1.

The broken lines are shown in the views for illustrative purposes only and form no part of the claimed design.
